ORNAMENTATION OF A PAIL.

No. 15,311.

Patented Aug. 19, 1884

UNITED STATES PATENT OFFICE.

SAMUEL W. WILLARD, OF NICOLET, WISCONSIN.

DESIGN FOR THE ORNAMENTATION OF A PAIL.

SPECIFICATION forming part of Design No. 15,311, dated August 19, 1884.

Application filed June 9, 1884. Term of patent 7 years.

To all whom it may concern:

Be it known that I, SAMUEL W. WILLARD, a citizen of the United States, residing at Nicolet, in the county of Brown and State of Wisconsin, 5 have invented and produced a new and original Design for Pails, of which the following is a specification, reference being had to the accompanying photograph, forming a part thereof.

My new design consists in the representation, 10 on the exterior surface of the pails, of fishes of various kinds and in various positions, substantially as represented in the said photograph.

Having thus described my design, I claim as new and desire to secure by Letters Patent of the United States—

The design for the ornamentation of pails, consisting of the representation of a series of fishes of various kinds and in various positions, substantially as shown and described.

SAMUEL W. WILLARD.
